(57) **CLAIM**

The front winker design for motor scooters thereof, as shown and described.

DESCRIPTION

FIG. 1: a front view of the front winker;

FIG. 2: a plan view of the front winker;

FIG. 3: a bottom view of the front winker;

FIG. 4: a right side view of the front winker;

FIG. 5: a perspective view of the front winker as seen from the right front side;

FIG. 6: a perspective view of the front winker as seen from the left front side; and,

FIG. 7: a perspective view of the front winker as seen from the right rear side.

The broken lines illustrate environmental structure only and form no part of the claimed design.
